CARTON HAVING TEAR STRIP IN COVER FLAPS
Kenneth T. Buttery and Thomas Vander Lugt, Jr., Kalamazoo, Mich., assignors to KVP Sutherland Paper Company, Kalamazoo, Mich., a corporation of Delaware

Filed Sept. 11, 1963. Ser. No. 308,198
11 Claims. (Cl. 229—51)

The present invention relates to cartons, and is more particularly concerned with a carton having a tear strip provided in its cover flaps, which carton may be readily erected from an integral cut and scored blank and sealed shut by means of automatic machinery.

Cartons having a so-called "flip top" cover hingedly connected to the edge of the rear panel, which may be erected with the cover in sealed condition and which may be readily opened by the removal of a tear strip, have become exceedingly popular, particularly as containers for food items such as ice cream. Once the tear strip is removed, the cover may be opened for access to some or all of the contents, and may be reclosed for further storage until the contents have been completely consumed. Cartons of the type described which have been available in the prior art, although satisfactory in use, have the disadvantage that they are difficult to construct and seal on automatic machinery.

Prior art cartons are generally provided with an outer front wall member integral with the cover of the carton, having its own flaps extending at the ends thereof. A tear strip is provided as an integral unit and extends from the end of one outer front wall flap, across the outer front wall, and to the end of the opposite outer front wall flap. Such a structure is difficult to construct into a carton from an integral blank and requires expensive machinery for the purposes of erection and sealing.

It is an object of the present invention to provide a top-opening carton which may be sealed and subsequently opened by the removal of a tear strip. It is another object to provide such a carton which may be readily reclosed when it is desired to store unconsumed contents. It is a further object to provide a carton of the type described which may be formed from an integral cut and scored blank. It is a still further object to provide a carton of the type described which can be readily erected and subsequently sealed by means of relatively simple and inexpensive machinery. The accomplishment of the foregoing and additional objects will become more fully apparent hereinafter.

The invention in its preferred embodiment is illustrated by the accompanying drawings in which:

FIG. 1 is a plan view of the cut and scored blank from which the carton is formed, viewed from the inside.

FIG. 2 is a perspective view of the carton with a portion of the tear strip removed; and

FIG. 3 is a perspective view of the carton with the tear strip completely removed, and with the cover partially open.

According to the invention, a carton is provided which may be formed from an integral blank, the cover of the carton having three cover flaps, each of the cover flaps having a separate tear strip formed therein comprised of spaced apart substantially parallel fracture lines. Two of the cover flaps are provided with terminal connecting flaps for affixing to the adjacent cover flap. When adhesive material is provided in the proper areas, and the cover flaps glued in place, a sealed carton may be formed having a continuous tear strip extending the entire length of the cover flaps, and wherein the entire tear strip may be removed with a continuous tearing motion. Because of the particular type of construction, the carton may be readily

2

erected, filled, and sealed with relatively simple and inexpensive machinery.

Reference is now made to the accompanying drawings for a better understanding of the invention, wherein all 5 of the parts are numbered and wherein the same numbers are used to refer to corresponding parts throughout.

In a preferred form, the carton of the invention is constructed from an integral blank as illustrated in FIG. 1. The structure comprises a rear wall member 1, a bottom member 2, and a front wall member 3 hingedly connected together at score lines. The rear wall member 1 and the front wall member 3 have lock flaps 4 and 5 hingedly connected at their ends. The lock flaps 4 comprise lock tongues 6 and beveled heels 7. The lock flaps 5 comprise lock tongues 8 and beveled heels 9. A pair of inner end wall flaps 10 are hingedly connected at the ends of the bottom 15. Each outer end wall flap 10 is provided with engagement slits 11 and 12 positioned to engage the lock tongues 6 and 8 when the carton is erected. A cover 13 is hingedly connected to the rear wall 1 at a score line. Cover flap members comprising outer end wall members 14 and 16 and an outer front wall member 15 are hingedly connected to the cover 13. Each cover flap is divided into three areas by a pair of spaced apart substantially 20 parallel fracture scores 17, 18 and 19. The areas comprise glue strips 20, 21 and 22, tear strips 23, 24 and 25, and cover flaps 26, 27 and 28. Two of the cover flap members 14 and 15 are provided with terminal extension flaps 29 and 30 having parallel fracture scores 31 and 32 positioned as extensions of the fracture scores 17 and 18. Glue is applied to the blank, as shown by stippled shading in FIG. 1, at the glue strips 20, 21 and 22, and at glue areas 33 and 34.

In assembling the carton, the lock tongues 6 and 8 of

35 the lock flaps 4 and 5 are inserted in the engagement slits 11 and 12 to form the body portion of the carton. This may be performed on conventional carton set-up machinery which is well known in the prior art and presently in use in commerce. The carton may then be filled

40 with the desired contents. The cover 13 is then closed over the top of the carton. The glue strip 20 of the outer end wall member 14 is then glued in position to its respective inner end wall member 10. The terminal extension flap 29 is then folded over the inner front wall member 3.

45 The outer front wall member 15 is then folded over the terminal extension flap 29 and the front wall 3, and the glue strip 21 is affixed to the bottom of the front wall 3. The glue area 33 which also covers a portion of tear strip 24 affixes the end of the outer front wall member 15 to the terminal extension flap 29, the tear strip 24 thus being 50 affixed to the tear-strip extension 35 formed by the fracture scores 31. The terminal extension flap 30 is then folded over the other inner end wall member 10. The outer end wall member 16 is folded over the connecting flap 30 and the inner wall member 10. The glue strip 22 is glued to the inner end wall member 10 and terminal extension flap 30. The glue area 34 is glued to the terminal extension flap 30, the tear strip 25 thus being affixed 55 to the tear strip extension 36 formed by the fracture scores 32. The result is a completely enclosed and sealed carton, with the tear strip of the three cover flaps being secured together in alignment.

The structure and sequence of assembly described 60 result in a carton wherein the terminal extension flaps 29 and 30 extend in the direction of tear. The lateral extension 29 is overlapped by and affixed to the cover flap member or outer front wall 15, and the terminal extension flap 30 is overlapped by and affixed to the cover flap or outer end wall 16. This insures the integrity of

65 the tear strip as it is removed. For example, as the tear strip 23 is being removed and reaches the corner

70 75 80 85 90 95

of the carton, the lateral extension 35 lifts the tear strip 24. Consequently, the glue bond connecting the tear strip extension 35 to the tear strip 24 is not stressed nearly as much as it would be if the arrangement were reversed. Even if the glue bond should fail, the lifting of the segment 23 will tear out the end of the tear strip 24, so that it can be subsequently grasped and removed. In contrast, if the end flaps were to be folded in first, followed by the cover flap 15, the glue joint would be the sole lifting means for the tear strip 24. As the tear strip rounded the corner, the tear strip extension 35 would be engaged with section 24 only by its glue bond. This would place an undue stress on the glue bond and, in case of its failure, the tear strip 24 would remain intact and could be engaged and torn off only with difficulty.

The carton is opened by engaging the tab 37 of the tear strip, as shown in FIG. 2. As a result of the structure described, the tear strips 23, 24 and 25 together with the tear strip extensions 35 and 36 form a unitary tear-strip structure. As a result, the entire tear-strip structure may be detached or ripped off with a single operation. Once the tear strip has been removed, the cover may be readily lifted at one end and opened, as illustrated in FIG. 3. If the contents of the carton are not immediately consumed, the cover may be reclosed and the carton stored until further use.

The fracture scores defining the tear strips may be formed by slits of any suitable configuration. However, in a preferred embodiment the slits are provided in the form of a V, each slit having a leg divergent with respect to the center of the tear strip in the direction of tear, terminating in a leg substantially parallel to the direction of tear and defining the outer boundary of the tear strip, the slit configurations on opposite sides of the tear strip preferably being staggered. Tear strips having fracture scores of this configuration tear readily and cleanly, and the line of tear is confined to its intended course. This is particularly important at the crease of the cover flaps where they are adhered to the tear strips of the terminal extensions of adjacent cover flaps. In the embodiment shown in the drawings the preferred configuration is provided only in the fracture scores of the cover flaps proper, since this generally suffices. However, if desired the preferred configuration may also be used to provide the tear strips in the terminal extensions.

The carton of the present invention has an advantage over prior art cartons of a similar type in that it may be readily erected and closed by means of simple machinery. This is made possible by the sequence and structure provided in the cover and cover flap members. To fully realize the advantages of the invention, it is important that only two connecting flaps be provided at the corners where the flaps are joined. Moreover, in order to provide for a sequential closing of the flaps, one connecting flap must be provided at the forward edge of one outer end wall member, as for example connecting flap 29 at outer end wall member 14. The other connecting flap must be provided at the opposite end of the outer front wall member, as for example connecting flap 36 at the end of outer front wall member 15. This permits cover flaps 14, 15 and 16 to be folded over and glued sequentially. It is of course apparent that the structure could be reversed, with a connecting flap being provided on the outer end wall member 16 and another connecting flap being provided on the opposite end of the outer front wall member 15. This would enable the structure to be formed sequentially in the opposite direction.

The carton of the present invention has a structure which renders it strong, rigid and capable of being readily assembled and sealed. It can be filled and sealed with simple and relatively inexpensive equipment, and eventually reopened by the removal of a unitary tear strip structure. The material and labor cost of the carton is

relatively low since it can be formed from an integral cut and scored blank.

It is to be understood that the invention is not limited to the exact details of construction, operation, or exact materials or embodiments shown and described, as obvious modifications and equivalents will be apparent to one skilled in the art, and the invention is therefore to be limited only by the scope of the appended claims.

We claim:

1. A carton formed of an integral blank cut and scored to provide a bottom member, a rear wall member, and an inner front wall member, end flaps attached to said members, and means securing said end flaps together, a cover hingedly connected to the upper edge of said rear wall member and provided with cover flaps comprising outer end wall members and an outer front wall member, two of said cover flaps having terminal extensions affixed to an adjacent cover flap, said cover flaps and said terminal extensions each being provided with a pair of spaced-apart substantially parallel fracturing scores defining a tear strip, said cover flaps being secured to said end flaps and said inner front wall member below the lower of said fracturing scores, and the tear strips of said cover flaps being adhesively secured together in alignment by the tear strips of said terminal extensions.

2. A carton comprising a bottom member, a rear wall member, and an inner front wall member, end flaps attached to said members, and means securing said end flaps together, a cover hingedly connected to the upper edge of said rear wall member and provided with cover flaps comprising outer end wall members and an outer front wall member, one of said outer end wall members having a terminal extension affixed to an end of said outer front wall member adjacent thereto, and the other end of said outer front wall member having a terminal extension affixed to the outer end wall member adjacent thereto, said cover flaps and said terminal extensions each being provided with a pair of spaced-apart substantially parallel fracture scores defining a tear strip, said cover flaps being secured to said end flaps and said inner front wall member below the lower of said fracture scores, and the tear strips of said cover flaps being secured together in alignment by the tear strips of said terminal extensions.

3. A carton formed of an integral blank cut and scored to provide a bottom member, a rear wall member, and an inner front wall member, end flaps attached to said members and means securing said end flaps together, a cover hingedly connected to the upper edge of said rear wall member and provided with cover flaps comprising outer end wall members and an outer front wall member, one of said outer end wall members having a terminal extension affixed to an end of said outer front wall member adjacent thereto and the other end of said front wall member having a terminal extension affixed to the outer end wall member adjacent thereto, said cover flaps and said terminal extensions each being provided with a pair of spaced-apart substantially parallel fracture scores defining a tear strip, said cover flaps being secured to said end flaps and said inner front wall member below the lower of said fracture scores, and the tear strips of said cover flaps being secured together in alignment by the tear strips of said terminal extensions.

4. A carton formed of an integral blank cut and scored to provide a bottom member, a rear wall member, and an inner front wall member, end flaps attached to said members and means securing said end flaps together, a cover hingedly connected to the upper edge of said rear wall member and provided with cover flaps comprising outer end wall members and an outer front wall member, one of said outer end wall members having a terminal extension overlapped by and affixed to an end of said outer front wall member adjacent thereto and the other end of said front wall member having a terminal extension overlapped by and affixed to the outer

end wall member adjacent thereto, said cover flaps and said terminal extensions each being provided with a pair of spaced-apart substantially parallel fracture scores defining a tear strip, said cover flaps being secured to said end flaps and said inner front wall member below the lower of said fracture scores, and the tear strips of said cover flaps being secured together in alignment by the tear strips of said terminal extensions.

5. A carton formed of an integral blank cut and scored to provide a bottom member, a rear wall member, and an inner front wall member, end flaps attached to said members and means securing said end flaps together, a cover hingedly connected to the upper edge of said rear wall member and provided with cover flaps comprising outer end wall members and an outer front wall member, one of said outer end wall members having a terminal extension affixed to an end of said outer front wall member adjacent thereto and the other end of said front wall member having a terminal extension affixed to the outer end wall member adjacent thereto, said cover flaps and said terminal extensions each being provided with a pair of spaced-apart substantially parallel fracture scores defining a tear strip, said fracture scores comprising a plurality of V-shaped slits each comprising a leg divergent with respect to the center of the tear strip in the direction of tear and terminating in a leg substantially parallel to the direction of tear and defining the outer boundary of said tear strip, said cover flaps being secured to said end flaps and said inner front wall member below the lower of said fracture scores, and the tear strips of said cover flaps being secured together in alignment by the tear strips of said terminal extensions.

6. A carton formed of an integral blank cut and scored to provide a bottom member, a rear wall member, and an inner front wall member, end flaps attached to said members and means securing said end flaps together, a cover hingedly connected to the upper edge of said rear wall member and provided with cover flaps comprising outer end wall members and an outer front wall member, one of said outer end wall members having a terminal extension extending in the direction of tear and overlapped by and affixed to an end of said outer front wall member adjacent thereto and the other end of said front wall member having a terminal extension extending in the direction of tear and overlapped by and affixed to the outer end wall member adjacent thereto, said cover flaps and said terminal extensions each being provided with a pair of spaced-apart substantially parallel fracture scores defining a tear strip, said fracture scores comprising a plurality of V-shaped slits each comprising a leg divergent with respect to the center of the tear strip in the direction of tear and terminating in a leg substantially parallel to the direction of tear and defining the outer boundary of said tear strip, said cover flaps being secured to said end flaps and said inner front wall member below the lower of said fracture scores, and the tear strips of said cover flaps being secured together in alignment by the tear strips of said terminal extensions.

7. A carton formed of an integral blank cut and scored to provide a bottom member, a rear wall member, and an inner front wall member, each of said members having a pair of end flaps, and means securing said end flaps together, a cover hingedly connected to the upper edge of said rear wall member and provided with cover flaps comprising outer end wall members and an outer front wall member, one of said outer end wall members having a terminal extension affixed to an end of said outer front wall member adjacent thereto and the other end of said outer front wall member having a terminal extension affixed to the outer end wall member adjacent thereto, said cover flaps and said terminal extensions each being provided with a pair of spaced-apart substantially parallel fracture scores defining a tear strip, said cover flaps being secured to said

end flaps and said inner front wall member below the lower of said fracture scores, and the tear strips of said cover flaps being secured together in alignment by the tear strips of said terminal extensions.

5 8. A carton formed of an integral blank cut and
scored to provide a bottom member, a rear wall mem-
ber, and an inner front wall member, each of said
members having a pair of end flaps, and means securing
said end flaps together, a cover hingedly connected to
10 the upper edge of said rear wall member and provided
with cover flaps comprising outer end wall members
and an outer front wall member, one of said outer end
wall members having a terminal extension affixed to an
end of said outer front wall member adjacent thereto
15 and the other end of said outer front wall member hav-
ing a terminal extension affixed to the outer end wall
member adjacent thereto, said cover flaps and said termi-
nal extensions each being provided with a pair of
spaced-apart substantially parallel fracture scores defin-
20 ing a tear strip, said fracture scores comprising a plu-
rality of V-shaped slits comprising a leg divergent with
respect to the center of the tear strip in the direction
of tear and terminating in a leg substantially parallel
to the direction of tear and defining the outer boundary
25 of said tear strip, said cover flaps being secured to said
end flaps and said inner front wall member below the
lower of said fracture scores, and the tear strips of said
cover flaps being secured together in alignment by the
tear strips of said terminal extensions.

30 9. An integral blank cut and scored to provide a carton comprising a bottom member, a rear wall member, and an inner front wall member, each of said members having a pair of end flaps, and means for securing said end flaps together, a cover hingedly connected to the
35 upper edge of said rear wall member and provided with cover flaps comprising outer end wall members and an outer front wall member, two of said cover flaps having terminal extensions adapted to be affixed to an adjacent cover flap, said cover flaps and said terminal extensions
40 each being provided with a pair of spaced-apart substantially parallel fracture scores defining a tear strip, said cover flaps being adapted to be secured to said end flaps and said inner front wall member below the lower of said fracture scores, and the tear strips of said cover
45 flaps being adapted to be adhesively secured together in alignment by the tear strips of said terminal extensions.

10. An integral blank cut and scored to provide a carton comprising a bottom member, a rear wall member, and an inner front wall member, each of said members having a pair of end flaps, and means adapted to secure said end flaps together, a cover hingedly connected to the upper edge of said rear wall member and provided with cover flaps comprising outer end wall members and an outer front wall member, one of said outer end wall members having a terminal extension adapted to be affixed to an end of said outer front wall member adjacent thereto and the other end of said outer front wall member having a terminal extension adapted to be affixed to an end of the outer end wall member adjacent thereto, said cover flaps and said terminal extensions each being provided with a pair of spaced-apart substantially parallel fracture scores defining a tear strip, said cover flaps being adapted to be secured to said end flaps and said inner front wall member below the lower 55 of said fracture scores, and the tear strips of said cover flaps being adapted to be secured together in alignment by the tear strips of said terminal extensions.

11. An integral blank cut and scored to provide a
carton comprising a bottom member, a rear wall mem-
ber, and an inner front wall member, each of said mem-
bers having a pair of end flaps, and means adapted to
secure said end flaps together, a cover hingedly con-
nected to the upper edge of said rear wall member and
provided with cover flaps comprising outer end wall
members and an outer front wall member, one of said

outer end wall members having a terminal extension adapted to be overlapped by and affixed to an end of said outer front wall member adjacent thereto and the other end of said outer front wall member having a terminal extension adapted to be overlapped by and affixed to the outer end wall member adjacent thereto, said cover flaps and said terminal extensions each being provided with a pair of spaced-apart substantially parallel fracture scores defining a tear strip, said cover flaps being adapted to be secured to said end flaps and said inner front wall member below the lower of said fracture scores, and the tear strips of said cover flaps being

adapted to be secured together in alignment by the tear strips of said terminal extensions.
